UNITED STATES PATENT OFFICE.

ELDEN P. LAMB, OF CAMDEN, MAINE, ASSIGNOR OF ELEVEN-TWENTIETHS TO JOHN BIRD, OF CAMDEN, MAINE.

CARBURETER.

1,257,888.

Specification of Letters Patent. Patented Feb. 26, 1918.

Application filed December 17, 1914, Serial No. 877,753. Renewed August 10, 1917. Serial No. 185,631.

To all whom it may concern:

Be it known that I, ELDEN P. LAMB, a citizen of the United States, residing at Camden, in the county of Knox and State 5 of Maine, have invented certain new and useful Improvements in Carbureters; and I do hereby declare the following to be a full, clear, and exact description of the invention, such as will enable others skilled in the art 10 to which it appertains to make and use the same.

This invention relates to carbureters and has for an object to provide a carbureter of improved type having improved means for 15 starting action with gasolene or similar light hydrocarbon and continuing the action with kerosene or other similar heavier hydrocarbon.

A further object of the invention is to 20 provide a device in general resembling the disclosure in pending application Serial No. 840,305, filed May 22nd, 1914, but involving an improved form of atomizing valve.

A further object of the invention is to 25 provide in a carbureter improved means for controlling the introduction and passage of the various hydrocarbons mentioned.

A further object of the invention is to 30 provide improved means for automatically regulating the supply of fuel to correspond with the volume of air introduced.

A further object of the invention is to 35 provide manual control for varying the relation automatically maintained between the air and fuel inlet.

With these and other objects in view the invention comprises certain novel constructions, combinations and arrangement of parts as will be hereinafter more fully 40 described and claimed.

In the drawings:

Figure 1 is a sectional view through the carbureter.

Fig. 2 is a view of the carbureter in side 45 elevation, the side indicated by arrow 2 at Fig. 1.

Fig. 3 is a view of the carbureter in side elevation taken at right angles to the view at Fig. 2 as indicated by arrow 3 at such 50 figure and also showing arrow 2 the position of Fig. 2 relative to Fig. 3.

Fig. 4 is a top plan view of the carbureter showing arrows 2 and 3 indicating the posi-

tions of Figs. 2 and 3 respectively, also showing line 1—1 the position of Fig. 1 55 above the line a b and the line 1'—1' showing the position of the section at Fig. 1 below the line a b.

Fig. 5 is a sectional view through the valve structure controlling the introduction 60 of fuel taken on line 5—5 of Figs. 1, 3 and 4.

Fig. 6 is a view of the atomizing valve, one-half being shown in plan and the other half being shown in section.

Fig. 7 is a view in side elevation of the 65 pipe automatically governing the relation of fuel and air.

Like characters reference designate 70 corresponding parts throughout the several views.

The improved carbureter which forms the subject-matter of this application resembles the carbureter disclosed in co-pending application 840,305, as above noted, in that a thin metal conical diaphragm 10 is employed 75 providing a space 11 for a thin film of hydrocarbon which passes from the chamber 12 through the opening 13 into said space and there spreads out into the thin film to be acted upon by the heat introduced 80

through the passage 14 deflected upwardly by the partition 15 into engagement with the diaphragm and thereby being deflected 85

downwardly to pass out of the passage 16 as described more fully in said co-pending 90

application. A scraper 17 is also employed in the form of a thin narrow strip of metal 95

mounted intermediate its ends upon the spindle 18 which extends outwardly through the housing of the carbureter and is provided 100

upon the exterior with a crank arm 19 so that such scraper may be rotated upon the spindle 18 as an axis and the wings of the 105

strip engaging against the under or inner surface of the diaphragm 10 to remove all 110

carbon deposit or other extraneous matter appearing thereon. It is intended to employ 115

this heating arrangement as disclosed in 120

said co-pending application and the use of 125

heavier hydrocarbons as for instance kero- 130

sene which are heated by the heating fluid, 135

as for instance the waste gases from the 140

motor to gasify such hydrocarbon or to 145

raise to such temperature that when it meets 150

with air it gasifies and mixes with the air as 155

is the case with lighter hydrocarbons. Just

whether the hydrocarbon is gasified in this space by the heat or whether it is simply raised to such a temperature that when mixed with air it gasifies cannot be definitely stated.

Whatever the action in regard to the action of the heat upon the fuel such fuel so heated passes upwardly through the passage 20 which is the opening in the pipe 21 shown 10 more particularly at Fig. 7. This pipe 21 is provided with a series of small openings spirally arranged as shown at 22 with a needle valve 23 inserted within such pipe and adjustable therein in any approved manner 15 as by the employment of the screw-threads 24. This needle valve extends upwardly through the housing and is provided upon the exterior with a knurled head 25 by which the flow of fuel around such needle 20 valve may be properly and manually adjusted.

Surrounding the pipe 21 is a sleeve 26 carrying the atomizing valve 27 which in general principles is similar to the atomizing valve disclosed in the said copending application 840,305 in that there are a plurality of radial ducts 27' leading outwardly from a central annular chamber 28 which embraces the pipe 21, such chamber existing only below the inner ends of the radial passages and not above so that as the valve 27 moves upwardly and downwardly upon the pipe 21 more or less of the openings 22 communicate with the radial chamber 28 25 and therefore with the radial passages 27'. As the fuel is introduced through the openings 22 it is obvious that more or less of the fuel will be introduced into the annular chamber depending upon the positions of 30 the atomizing valve 27, the higher the valve is raised the more of the openings being uncovered so that more of the fuel passes into the annular chamber and therefore outwardly through the radial passages. The 35 atomizing valve 27 is held normally to seat by a spring 29 which is inclosed within the sections 30 and 31 of a telescoping shell, the latter being controlled by a manual lever 32 so that the tension of the spring 29 upon the 40 atomizing valve 27 may be manually varied as found expedient.

About the atomizing valve 27 an annular series of openings 33 are provided tapered from both sides as indicated more particularly at Fig. 1 transecting some of the radial passages 27', shown at Fig. 6 as transecting alternate passages although it is to be understood that the number and relation of such passages transected is immaterial to 45 the invention. Intermediate the openings 33 the periphery of the atomizing valve 27 is provided with grooves 34 formed in the beveled under side of such periphery producing thereby openings between the periphery of the valve and its seat register-

ing with the external end of certain of the passages 27' so that at all times even when the atomizing valve 27 is seated as shown in full lines at Fig. 1 there are openings through the tapered holes 33 and through 50 the grooves 34 for the passage of air directed and restricted to pass directly over the radial passages. By this means even when there is a very small quantity of air passing through the carburetor the opening is 55 so restricted that it does not pass through the entire peripheral space surrounding the atomizing valve 27 but is localized to pass directly over the extremities of the feed passages 28 so that even this small amount of 60 air will be highly charged with the hydrocarbon gases. It will be noted, especially with Fig. 1 that when the atomizing valve 27 is on its seat only the lowermost one of the openings 22 is in communication with 65 the annular chamber 28 and therefore with the radial passages 27' so that only the minimum of fuel is fed to the atomizing valve when the valve is on its seat. As the valve is raised by the pressure of air below 70 through the passage 35 the valve is raised admitting fuel to correspond with such air volume. The air is introduced in a thin film surrounding the gas inlet passage, as indicated at 36 and is further heated by engagement with the walls of the heat chamber.

The air after passing by the atomizing valve 27 and taking up the hydrocarbon vapors passes upwardly into the mixing chamber 36 and outwardly through the passage 100 37 to the motor, such passage being controlled by the valve 38 and the manual lever 39, in the usual well known manner.

The passage of the fuel hydrocarbon from its source of supply is regulated by a valve 105 mechanism shown in section at Fig. 1 and also at Fig. 5. Conduits 40 and 41 supply the fuel to the valve housing 42 as indicated the conduit 40 being intended to convey the gasoline or light hydrocarbon while the conduit 41 is intended to convey the heavier or main fuel supply.

Within the valve housing a tapered turning plug 43 is mounted controlled by a manual lever 44. This turning plug 43 is 115 provided with a circumferential groove 45 extending somewhat more than one-half way around the valve and in position to communicate with the conduits 40 and 41 according to its position and also to communicate with the passage 46 leading to the filter 47 which in turn communicates with the annular chamber 48 which is open to the chamber 12. It will be apparent, therefore, that as the valve 43 is rocked from the position 125 marked Gasoline to the position marked Kerosene at Fig. 5 the groove 45 will interrupt communication there established between the passage 40 and 46 and will establish communication between the passages 41 130

and 46 thereby cutting off the supply of gasoline from the fuel chamber 12 and supplying in its stead the heavier hydrocarbon.

At starting, however, it is desirable to supply the light hydrocarbon direct to the mixing chamber 36, such action being known as flushing. For this purpose the valve 43 is provided with a groove 49 extending longitudinally thereof and in position to establish communication between the passage 40 and the passage 50, shown at Fig. 1 which said passage 50 is in communication with the passage 51 leading directly to the mixing chamber. When, therefore, the valve 43 is rocked to the position shown as Flush at Fig. 5 the groove 49 is in communication with the passages 40 and 50 so that the gasoline passes directly from the passage 40 to the mixing chamber without passing through the atomizing valve. As shown at Fig. 1 a passage 51' is disclosed. It will be noted especially from Fig. 4 that the top portion or mixing chamber of this atomizer is capable of being turned to any one of four positions by reason of the fact that the screws 52 by which said mixing chamber is secured to the body of the atomizer are equally spaced. This turning of the mixing chamber permits the device to discharge the mixture of fuel and air to any quarter desired. The passages 51' are therefore provided so that when the mixing chamber is turned to any one of its four positions one of such passages will always register with the passage 50 for the purpose of flushing.

Many mechanical features common in such devices the functions of which are perfectly apparent from the drawings have not been specifically mentioned or described, as for instance the butter-fly valve 52 in the hot air passage controlled by the manual lever 53, the latch 54 for maintaining the knurled head 25 in position, the float 55, lever 56 and needle valve 57 for controlling the passage of the fuel from the annular chamber 48 to the chamber 12 and various common mechanical expedients shown in conjunction with these and other elements of the drawings, the utility and functions of which will be readily understood without encumbering the record with a description of the same.

In operation to start the motor the manual lever 44 is first thrown to the position shown as "Flush" at Figs. 2 and 5 whereby the lighter hydrocarbons are admitted directly from the source of supply to the mixing chamber to flush the same. From this position the manual lever is thrown to the position marked "Gasoline" in the figures mentioned whereby the lighter hydrocarbons still pass through the various intermediate passages and outwardly through the atomizing valve 27 in engagement with the air which passes through the openings 36 and 35. After the motor is started on this

lighter hydrocarbon the heated gases from this source or to be sure any other source which is convenient is introduced through the passages 14 to heat the film of fuel in the space 11. The manual lever is now thrown to the position marked "Kerosene" whereby the heavier oils are supplied and being heated as above pass upwardly through the atomizing valve and are taken up by the air as before mentioned.

I claim:

1. In a carbureter, a valve housing embodying a valve seat; a valve positioned to engage with the seat and having radial passages extending therethrough, said radial passages communicating also with air passages formed in the valve adjacent its periphery.

2. In a carbureter, a valve housing embodying a valve seat; a disk valve having radial passages extending substantially at right angles to its axis with reversely tapered openings extending through the valve and transecting some of said radial passages; others of said passages extending to the periphery of the valve.

3. In a carbureter, a valve housing embodying a valve seat; a disk valve proportioned to engage with the seat and provided with radial passages extending from the center to the periphery and also provided upon its periphery with grooves transecting the extremities of some of said radial passages and forming openings at all times between the valve and its seat.

4. In a carbureter, a valve housing embodying a valve seat; a disk valve yieldingly mounted upon the seat and provided with radial passages, said valve also being provided with openings extending through such valve and transecting some of said radial passages; and with grooves formed in the underside of the periphery of such valve and transecting the extremities of others of said radial passages.

5. In a carbureter, a valve housing embodying a fuel chamber; a pipe extending from the fuel chamber and provided with a series of openings; a sleeve embracing the pipe and having an annular chamber communicating with some of said openings; the number of said openings in communication being regulated by the sleeve relative to the pipe; and a valve carried by the sleeve having radial passages in communication with the annular chamber.

6. In a carbureter, a valve housing embodying a valve seat; a pipe extending upwardly through the valve seat and in communication with the fuel supply, said pipe being provided with a series of openings differently spaced from the bottom; a sleeve embracing said pipe and provided with an annular chamber in communication with some of said openings, the number of said

- openings in communication with the chamber being regulated by the vertical position of the sleeve; and a valve carried by the sleeve proportioned to interact with the 5 valve seat and provided with radial passages in communication at their inner ends with the annular chamber and terminating at their outer ends at the periphery of the valve.
- 10 7. In a carbureter, a valve housing embodying a valve seat; a fuel suply pipe extending upwardly through the valve seat and provided with a series of openings differently spaced from the bottom of the 15 pipe; a sleeve embracing and sliding upon the pipe and provided with an annular chamber in communication with a number of said openings controlled by the vertical position of the sleeve relative to the pipe;
- 15 20 a valve carried by the sleeve and proportioned to interact with the valve seat and provided with radial passages in communication with the annular chamber; some of said passages extending entirely to the periphery of the valve, said valve being also provided with openings therethrough transecting others of said radial passages.
- 20 8. In a carbureter, a valve housing provided with a valve seat; a fuel supply pipe 30 extending upwardly through the valve seat and provided with a series of openings differently spaced from the bottom; a sleeve embracing the pipe and provided with an annular chamber in communication with some of said openings, the number being controlled by the vertical position of the sleeve; a valve carried by the sleeve and proportioned to interact with the valve seat 35 and provided with a plurality of radial passages communicating at their inner ends with the annular chamber, some of said passages extending to the periphery of the valve adjacent to grooves formed in such periphery, and others of said passages ter-
- minating at openings formed through said valve; a spring exerting yielding tension upon the valve to hold it normally to seat; and manual means for varying the tension of the spring.
9. In a carbureter, a valve housing provided with a plurality of fuel ducts; a valve mounted to rotate in said housing and provided with a circumferential groove extending part way around said valve and with a longitudinal groove communicating with said peripheral groove, said grooves being arranged so that when the valve is in one position one of the fuel inlets is in communication with one outlet, when in a different position the same fuel inlet is in communication with a different outlet and when in a third position the second fuel inlet is in communication with the last mentioned outlet.
10. In a carbureter, a valve seat; a disk valve coöperating with the seat and having an upwardly extending axial sleeve; a telescoping tube embracing the sleeve; a spring embraced by the telescoping tube and bearing upon the sleeve; and a manual lever adapted to control one of the telescoping sections.
11. In a carbureter, a fuel supply pipe having an internal passage embodying a valve seat; a needle valve inserted within the passage and manually controlled relative to the seat; a sleeve sliding upon the tube and provided with an annular chamber in communication with passages extending through the supply pipe above the valve; and radial passages formed in the valve communicating with the annular chamber.
- In testimony whereof I affix my signature in presence of two witnesses.
